UNITED STATES PATENT OFFICE.

DANIEL L. CHANDLER, OF AYER, MASSACHUSETTS, ASSIGNOR TO FITCHBURG BOBBIN CLEANING MACHINE CO., OF FITCHBURG, MASSACHUSETTS, A CORPORATION OF MASSACHUSETTS.

BOBBIN-STRIPPING MACHINE.

1,147,678.

Specification of Letters Patent. Patented July 20, 1915.

Application filed March 5, 1914. Serial No. 822,698.

To all whom it may concern:

Be it known that I, DANIEL L. CHANDLER, a citizen of the United States, residing at Ayer, in the county of Middlesex and State 5 of Massachusetts, have invented a new and useful Bobbin-Stripping Machine, of which the following is a specification.

This invention relates to a machine for stripping the filling from bobbins and the 10 principal objects thereof are to provide a practicable and efficient machine capable of operating at a sufficiently high speed to take care of all the bobbins that a person can supply to the machine; to provide a construction in which the bobbins can be placed in position, one at a time but not necessarily exactly in synchronism with the operation 15 of the machine so that the operator applying the bobbins can have considerable liberty to vary the speed of his actions; to provide a construction in which after the bobbins are placed in the machine in a definite place by the operator they will not again be released and the machine will not have to 20 depend for its effective operation upon any free movement of the bobbins themselves; to provide for positively forcing the bobbin stripping jaws against the bobbin at the beginning of the stripping operation so that 25 they will certainly engage the filling at the large end of the bobbin and positively clear it from that end and yet force the jaws against the bobbin under yielding pressure during the remainder of the motion so 30 as to avoid unnecessary wear and tear on the bobbins; to provide an arrangement whereby the stripping operation will be of the same efficiency independently of the length of the bobbin and whereby the bobbin 35 is held during the final operation of the stripping mechanism positively in position without the interposition of any moving parts; to provide positive and effective means for getting rid of the waste in such a 40 way that it cannot possibly interfere with the operation of the machine in any way; and to deposit the bobbins in another part without the employment of any mechanism for dislodging them.

50 The invention also involves improvements in details of construction of these and other parts of the machine and especially in the

combination of mechanism whereby these several parts are engaged to coöperate effectively with each other.

55

Reference is to be had to the accompanying drawings in which—

Figure 1 is a plan of a bobbin stripping machine constructed in accordance with this invention; Fig. 2 is a side elevation of the 60 same; Fig. 3 is a side elevation of the stripping mechanism proper on enlarged scale; Fig. 4 is a similar view showing the parts in another position; Fig. 5 is a plan of the same; Fig. 6 is a fragmentary plan of a 65 portion of the mechanism shown in Fig. 5 with the parts in another position; Fig. 7 is a side elevation of the guides and switches for the jaw operating mechanism; Fig. 8 is a side elevation of a detail thereof; Fig. 9 70 is a side elevation of one of the bobbin stripping jaws on enlarged scale; Fig. 10 is an end elevation of the same; Fig. 11 is a plan of a portion of the mechanism for operating the bobbin holding wheel, and 75 Fig. 12 is a side elevation thereof.

The machine is shown as mounted on a frame 10 and as provided with a shaft 11 receiving power from a pulley 12 and transmitting it through gears 13 to a main shaft 80 14. In whatever way this shaft receives power it has two functions, first, to feed the bobbins, and second, to operate the bobbin stripping mechanism. For accomplishing the first purpose, this shaft is provided with 85 a cam 15 which engages a lever 16 and swings it with a certain predetermined motion. Pivotally connected with the lever is a link 17 which has on the end thereof an arm 18. This arm is pivoted to and supported by an arm 19 which is pivoted on a shaft 20 located on the frame and parallel with the shaft 14. Integral with the arm 19 is another arm 21 which is pulled down by a spring 22 connected with the lower part 90 of the frame. On the shaft 20 is also a wheel 23 which constitutes an endless carrier for bobbins, and is provided with a series of radial pins 24 for receiving the bobbins to be stripped. The inner edge of this wheel 100 is provided with a series of notches 25.

The frame is provided with a projection 26 on which is pivoted a latch 27 mounted to swing in a horizontal plane and pressed

by a spring 28 toward the edge of the wheel. The end of the latch can engage in the notches 25 as they come around into position. However, the end of the arm 21 is 5 provided with a cam 29 adapted to engage the operative edge of the latch and force it away from the circumference of the wheel at times as will appear hereinafter, and then allow it to be retracted. This arm 21 has 10 an integral projection 30 for engaging the top of the latch and limiting its downward motion. The other arm 19 is provided with a radial stud 31 on which is pivoted a pawl 32 pressed by a spring 33 into contact with 15 the edge of the wheel so that it can enter the notches 25. As will appear from the description of the operation which will be given later, the vibrations of the lever 16 cause the wheel to be rotated intermittently 20 and the latch locks it in certain positions and then releases it.

The wheel is provided with a series of springs 35 each one fixed to the circumference of the wheel and having a perforation 25 for one of the pins 24. These springs normally hold the bobbin slightly away from the circumference of the wheel until positively forced up toward it.

The rest of the operations controlled by 30 the shaft 14 are under control of a crank 40 operating a link 41, which in turn is pivoted to a slide 42. This slide moves in guides 43 horizontally arranged on the side of the frame 10 and the slide is arranged in vertical position on the side of the machine.

It will be understood, of course, that one of the pins 24 with a bobbin thereon is brought by the mechanism previously above described into horizontal position shown in 40 Fig. 2 and that the slide then acts for the purpose of performing the bobbin stripping functions. For this purpose the slide is provided with a pair of pivoted jaws 44 one above and the other below the central line 45 of the slide. These jaws have hooks 45 extending from them in opposite directions and these hooks are connected by a spring 46 for normally holding the jaws together when there is nothing to resist the same. 50 The guides 43 are provided near the end thereof with a flat horizontal rail 47 having a thin part 48 at the center thereof, and a thick part 49 near each end. Above and below this rail is a pair of horizontal tracks 55 50 spaced from it. Each of these tracks is provided with a pivoted switch 51 curved over into contact with the rail 49 at its inner end. These switches are provided with projecting pins 52 connected by a spring 53 for 60 yieldingly forcing them into the position shown in Figs. 3 and 7. On the extreme ends of the jaws 44 are a pair of projections 54 extending at right angles to the planes of these jaws into position to be guided by the 65 rail 48 and tracks 50. On each of the jaws

44 also is pivoted a waste-removing jaw 55. This is provided with a plate 56 having a concave sharp edge adapted to engage the waste and remove it as will appear hereinafter. A spring 57 is provided for forcing 70 each of these jaws 55 toward the other, this spring being adjustable by a plate 58 and screw 59. A pair of stops 60 and 61 are provided for limiting the motions of each jaw 55. 75

For the purpose of removing the waste from the machine and throwing it to one side the following mechanism is provided:— On the frame 10 is fixed a bracket 63. Pivoted at 64 on this bracket is a flat ended stud 65 provided with a trigger 66. The reciprocations of the slide 44 are intended to operate these parts and for that purpose the slide is provided with a lever 67 pivoted thereon operated by a spring 68 up against 85 a stud 69 moving with the slide. On the stud 65 is a cylindrical slide 70 pivotally connected with an operating arm 71 which is pivoted on a stud 72 on the bracket 63. A spring 73 normally moves this arm 71 in 90 such a direction as to force the slide 70 and stud 65 back into the position shown in Fig. 5. An annular cam 74 is provided on the slide 42 for positively operating the slide 70 back into that position by engaging a pin 95 75 on the link 71, in case the spring does not do the work completely.

The operation of the entire machine is as follows: As the wheel 23 rotates intermittently the attendant supplies bobbins to the pins 24. The rotation of the cam 15 operates through the link 17 and connected parts to oscillate the lever 19—21. As the link 17 moves to the right in Fig. 2 the arm 19 is swung down and its pawl 32 moves back into a position enabling it to enter one of the notches 25. During this motion the spring 28 holds the latch 27 in one of the notches 25 and positively prevents rotation of the wheel 23, but just before the link 17 comes to the end of its stroke the cam 29 engages the latch and forces it back to unlock the wheel, and it is at this time that the pawl 32 enters another one of the notches 25. Any further motion of the link 17 in the same direction would cause the depression at the top of the cam 29 to come in front of the latch 27 and allow the pawl to move back of the notch 25. Of course, the projection at the top of the cam would prevent the spring 22 pulling these parts too far over independently of the cam 15. When the link 17 starts to move back the cam 29 will again unlock the latch 27 and at the same time the pawl 23 comes against the edge of the notch 25 in which it is engaged and positively moves the wheel around one space, that is, a distance equal to the distance between two of the pins 24. It takes, of course, the entire forward motion of the link to 115 120 125 130

accomplish this motion. There is no need of the cam 29 having any great length because just as soon as the wheel has turned slightly the edge of the wheel itself will 5 hold the latch 27 back. As soon as the wheel has turned one space this latch will automatically come into its locking position by engaging in the next notch 25 and holding the wheel in that position. Then the 10 link 17 is caused to start back by the spring 22 controlled by the cam 15, and the sequence of operations is repeated. It will be seen that the notches in the edge of the wheel and the other parts are so placed that every 15 time the wheel stops one of the pins 24 is in horizontal position at the front of the wheel. While these operations are taking place the crank 40 is also performing its functions. During the withdrawal, or motion of the 20 link 17 to the left, the crank is passing upwardly on the left-hand side of the shaft 14 as shown in Fig. 2 and is getting ready to force the slide 42 over to the right. During the right hand motion of this slide the 25 projections 54 on the jaws 44 engage the outer edges of the switches 51 and these jaws are forced apart. As the jaws 55 now rest against the stops 60 it will be clear that these jaws also are held apart. During 30 almost the entire motion of the slide 42 in this direction these jaws are kept out of contact with the bobbin on the horizontal pin 24 and also out of contact with the filling thereon. When the projections 54 come 35 to the end of the tracks 50 on which they slide from the switches 51 they are caused by the spring 46 to swing toward each other rapidly, and the projections 54 engage the rail 49. At this time the jaw plates 56 are 40 forced by the spring 46 into intimate contact with the bobbin at its large end behind the mass of filling thereon, and any further motion of the slide in that direction simply causes the bobbins to be pressed back against 45 the spring 35. By this time the crank 40 has reached the end of its stroke in this direction and the slide starts back. During the first, that is, the slow part of its motion back, the jaw-plates 56 grip the filling on 50 the bobbin positively, removing it therefrom. The projections 54 fit between the inner sides of the tracks 50 and the enlargements 47 so that they cannot move apart. Soon they come over the thin part 55 48 of the rail and then they are free to move toward each other a slight distance. Thus the jaws act positively at first while the large part of the bobbin is being stripped, but afterward act with a yielding pressure 60 on the smaller part. This is a feature of importance because the filling is positively started from the large end of the bobbin and yet it reduces the wear on the bobbins as well as that on the edges of the jaws, and I 65 have found in practice that on this machine

at least it results in absolutely accurate work. It will be understood, of course, that the switches 51 yield against the spring 56 to allow the projections 54 to pass on to the thickened end of the rail 49 near the end 70 of the stroke of the slide, so that they are then in position to be moved out by the switches on the reverse stroke, and so as to cause them to escape the end of the slide 65.

It will be understood that the pulling of 75 the filling from the bobbin when the latter is merely supported loosely on one of the rods 24 ordinarily will cause the bobbin to move from the rod. In order to hold the bobbin and to provide for receiving the 80 waste, the stud 65 is located in alignment with the bobbin when in this position. The operation of the jaws results in pulling the end of the bobbin up against the end of this stud so that the filling is moved on the stud 85 and left thereon by the jaws when they start to return. During the motion of the slide 42, to the left in Figs. 4 and 5 the upper end of the lever 67 engages the trigger 66 and has no effect on the latter because it is 90 moved over in that direction as far as it can owing to the presence of the cam 74. The lever 67 yields to allow its upper end to pass the trigger 66. Upon the reverse motion, however, the lever 67, being up against 95 the stop 69, the trigger 66 is forced around to the right in Fig. 5, and the stud 65 is swung into the position shown in Fig. 6. At the same time the clearer slide 70 is moved 100 out by the same motion and forces the filling from the stud 65 and drops it. After the lever 67 has accomplished this result and passed by the trigger 66, the spring 73 forces the parts back into the position shown in Fig. 5. If, however, this is not accomplished 105 the slanting inner edge of the cam 74 engages the pin 75 and positively forces these parts back into position ready for the next operation.

It will be seen that by this arrangement 110 the bobbins can be placed on the rods 24 by an operative in a rapid manner, but not necessarily with absolute regularity, and the parts will operate with bobbins of greatly varying lengths. Moreover, if the operative 115 fails to get a bobbin into place it will have no bad effect on any part of the mechanism, and he cannot put a bobbin in the wrong position. Even if it is not lodged clear down in the right position on the rod, yet 120 there is sufficient space between it and the stud 65 to permit the parts to work and the jaws 56 will engage the filling and force the bobbins back in proper position as they come up. It will be seen also that the jaws 125 are not positively forced to engage the bobbin at any part of their stroke except at the first of it where they must do that in order to start the main part of the filling which is usually at the end.

Another advantage lies in the fact that the operative does not have to attend to the machine as all of its working is automatic, and a further advantage lies in the fact that 5 the bobbins slide off the rods automatically and are deposited in a basket below, and the filling is forced away from the machine and dropped in another place.

Although I have shown and described 10 only a single embodiment of the invention I am aware of the fact that many modifications can be made therein by any person skilled in the art without departing from the scope of the invention as expressed in 15 the claims. Therefore, I do not wish to be limited in these respects, but

What I do claim is:—

1. In a machine for stripping filling from bobbins, the combination of an endless carrier having means thereon for receiving the bobbins, two arms, one provided with means for positively moving the carrier along intermittently, a cam on the other arm, a latch for locking the carrier in position after it 25 has been moved by the first named arm, means operated by said cam for unlocking the latch, and means for simultaneously moving said arms.

2. In a machine for stripping filling from 30 bobbins, the combination of a carrier having means thereon for receiving and holding the bobbins, a lever having means for positively moving the carrier, means for moving the lever intermittently, a latch for locking the 35 carrier in position and a cam movable with said lever for unlocking the latch.

3. In a machine for stripping filling from bobbins, the combination of a wheel having 40 pins radially projecting therefrom for receiving bobbins, means for intermittently rotating said wheel, a stripping mechanism located adjacent to said wheel, means for engaging the wheel and positively locking it in fixed position every time a pin comes into 45 registration with the stripping mechanism, and a cam for unlocking said locking means.

4. A bobbin carrier for a stripping machine comprising a rotary wheel having a 50 series of radial pins projecting therefrom for receiving the bobbins, and springs at the bases of the pins for receiving the ends of the bobbins for yieldingly holding the bobbins away from the wheel.

5. In a machine for stripping filling from 55 bobbins, the combination of a rotary wheel having means thereon for receiving bobbins, a cam, a link operated by said cam to reciprocate, a lever pivoted on the axis of said wheel and connected with said link to be 60 oscillated thereby, said lever having two arms, one of said arms being provided with means for positively moving the wheel around a portion of a revolution for each oscillation of the lever, a latch for locking 65 said wheel in position, and a cam on the

other arm of said lever for unlocking the latch.

6. In a machine for stripping filling from bobbins, the combination of a wheel having means thereon for receiving the bobbins, 70 said wheel having notches in one edge thereof, a lever having two arms oscillating on the axis of said wheel, a spring-pressed pawl on one of said arms for engaging said notches and forcing the wheel around, a spring- 75 pressed latch for engaging in the notches and holding the wheel in fixed position, and a cam on the other arm in position to engage said latch and force it out of its notch when the pawl moves into a notch, whereby the 80 wheel will be unlocked and the pawl will be free to move it forward.

7. In a machine for stripping filling from bobbins, the combination of a wheel for supporting the bobbins, said wheel having 85 notches in one edge thereof, a lever having two arms oscillating on the axis of said wheel, a spring-pressed pawl on one of said arms for engaging said notches and forcing the wheel around, a spring-pressed latch for 90 engaging in the notches and holding the wheel in fixed position, a cam on the other arm in position to engage said latch and force it out of its notch when the pawl moves into a notch, a cam for positively forcing 95 said lever in a direction to turn the wheel forward, and a spring connected with said lever for moving it in the other direction.

8. In a machine for stripping filling from bobbins, the combination of a wheel having 100 means thereon for receiving the bobbins, said wheel having notches in one edge thereof, a lever, a spring-pressed pawl on said lever for engaging said notches and forcing the wheel around, a spring-pressed latch for 105 engaging in the notches and holding the wheel in fixed position, and a cam on the lever in position to engage said latch and force it out of its notch when the pawl moves into a notch, whereby the wheel will be unlocked and the pawl will be free to move it 110 forward.

9. In a machine for stripping filling from bobbins, the combination of a carrier for receiving the bobbins and movable into position for stripping, a slide movable toward the carrier when in said position, a pair of jaws on said slide, means for forcing said jaws toward each other, a pair of tracks which said jaws engage as they move toward the bobbins, and a rail for receiving said jaws at the ends of said tracks and preventing their moving beyond a certain point toward each other.

10. In a machine for stripping filling from 125 bobbins, the combination of a carrier for bobbins having pins thereon for receiving the bobbins movable into stripping position, a slide movable in line with one of said pins when in stripping position, a pair of jaws 130

- on said slide, yielding means for forcing said jaws toward each other, a pair of rails for engaging said jaws and holding them apart when the jaws move forward toward 5 a pin, a track between said rails for receiving the jaws when they leave the rails to limit their motion toward each other, and a pair of switches connected with said tracks for forcing the jaws from the rails on 10 their forward motion, said switches being yieldingly mounted to permit the jaws to move out from under them on their reverse motion.
11. In a machine for stripping filling from 15 bobbins, the combination of a reciprocable slide, a pair of jaws pivoted on said slide, means whereby when said slide moves forward, said jaws are forced apart positively until the slide reaches substantially the end 20 of its travel, yielding means for forcing said jaws toward each other at this time, means for positively preventing the jaws from engaging each other and for holding them a slight distance apart during the entire 25 travel of the slide in the reverse direction, a pair of filling engaging jaws, one pivoted to each of the other jaws, springs for forcing said filling engaging jaws toward each other, and positive stops for 30 preventing the filling engaging jaws from engaging each other at all times.
12. In a machine for stripping filling from bobbins, the combination of a pair of stripping jaws movable along the bobbin, means 35 for positively holding the jaws against the bobbin during the first part of the stroke, and means for yieldingly holding them against it thereafter during the stroke.
13. In a machine for stripping filling from 40 bobbins, the combination of a pair of jaws movable toward and from stripping position, means for positively holding said jaws in contact with the large end of a bobbin during the first part of the stroke, and 45 means whereby they grip the bobbin yieldingly during the remainder of the stroke.
14. In a machine for stripping filling from bobbins, the combination of a pair of jaws, means for producing a relative longitudinal 50 motion between said jaws and a bobbin to be stripped, positive means for forcing said jaws into contact with the large end of the bobbin and for holding them positively in that position during the first part of the 55 operative stroke, whereby as they approach the small end of the bobbin they will be free to move toward the axis thereof, and springs for normally forcing them toward each other during the last part of the stroke.
- 60 15. In a machine for stripping filling from bobbins, the combination of a pair of stripping jaws movable along the bobbin, means for positively holding the jaws against the bobbin during the first part of the stroke, 65 means for yieldingly holding them against it thereafter during the stroke, a stud located in position to engage and hold the end of the bobbin when moved forward by said jaws, and means whereby the jaws are forced apart positively just before they reach said 70 stud.
16. In a machine for stripping filling from bobbins, the combination of a frame, a slide movable thereon, a bobbin support on the frame, jaws on said slide for engaging 75 the bobbin at the end of the stroke of the slide, means for positively preventing said jaws from engaging the bobbin materially before the end of the stroke, a stud mounted on the frame in position to receive the end of the bobbin and to receive the filling therefrom, and means for moving said jaws back to draw the filling from the bobbin on said stud.
17. In a machine for stripping filling 80 from bobbins, the combination of a frame, a carrier wheel rotatably mounted on the frame and having pins projecting therefrom for receiving bobbins, a spring at the base of each pin for yieldingly holding the end of the bobbin, a slide on the frame movable toward and from the carrier wheel, a stud mounted on said frame in line with the pins when they are in position for stripping, and means on said slide for engaging 85 the filling on the bobbin and pulling the filling and bobbin against the end of said stud, whereby the stud acts as a stop for the bobbin and receives the filling.
18. In a machine for stripping filling 90 from bobbins, the combination of a carrier, having pins projecting therefrom for receiving bobbins, a spring at the base of each pin for yieldingly holding the end of the bobbin, a slide movable toward and from the carrier, a stud in line with the pins when they are in position for stripping, and means on said slide for engaging the filling on the bobbin and pulling the filling and bobbin against the end of said stud, whereby the 95 stud acts as a stop for the bobbin and receives the filling.
19. In a machine for stripping filling 100 from bobbins, the combination of a frame, a slide movable on said frame, a bobbin carrier having a pin for receiving a bobbin, a stud pivoted on said frame in alinement with said pin, means on the slide for removing the filling from the bobbin and forcing it on said stud, and means for moving said 105 stud outwardly from the slide to deposit the filling therefrom.
20. In a machine for stripping filling 110 from bobbins, the combination of a frame, a slide movable on said frame, a bobbin carrier having a pin for receiving a bobbin, a stud pivoted on said frame in alinement with said pin, means on the slide for removing the filling from the bobbin and forcing it on said stud, and a trip-lever on 115 120 125 130

the slide for operating said stud to swing it outwardly as the slide moves up toward said pin.

21. In a machine for stripping filling from bobbins, the combination of a frame, a slide movable on said frame, a bobbin carrier having a pin for receiving a bobbin, a stud pivoted on said frame in alinement with said pin, means on the slide for removing the filling from the bobbin and forcing it on said stud, a clearing device on said stud, and means whereby as the slide moves up toward the pin the clearing device will move along the stud and the stud will swing out on the frame whereby the filling will be removed from the stud and deposited.
22. In a machine for stripping filling from bobbins, the combination of a frame, a bobbin carrier having a pin for receiving a bobbin, a stud pivoted on said frame in alinement with said pin, means for removing the filling from the bobbin and forcing it on said stud, a clearing device on said stud, means whereby the clearing device will move along the stud and the stud will swing out on the frame to remove the filling

from the stud and deposit it, and yielding means for forcing said clearing device and stud back to operative position after the operation thereof.

23. In a machine for stripping filling from bobbins, the combination of a bobbin carrier having a pin for receiving a bobbin, a pivoted stud in alinement with said pin, means for removing the filling from the bobbin and forcing it on said stud, means for moving said stud outwardly to deposit the filling therefrom, a clearer on the stud, means for swinging the stud out and moving the clearer along the stud to remove the filling therefrom at one side, yielding means for forcing the clearer and stud back into normal position, and positive means for forcing the clearer and stud back.

In testimony whereof I have hereunto set my hand, in the presence of two subscribing witnesses.

DANIEL L. CHANDLER.
